CLAIM

The ornamental design for a connector for printed circuit boards, as shown and described.

DESCRIPTION

FIG. 1 is a top plan view;

FIG. 2 is a front elevation;

FIG. 3 is a bottom plan view;

FIG. 4 is a rear elevation;

FIG. 5 is a left-side elevation;

FIG. 6 is a right-side elevation; and,

FIG. 7 is a frontal perspective view.

The present design is characterized in that, in addition to its generally two-storied configuration, there are two extensions jutting from the opposite upright edges of its right-hand wall, wherein one of the extensions lies in parallel with the connector body, with the other extension protruding in a direction perpendicular thereto.
